UNITED STATES PATENT OFFICE.

RICHARD W. UHLIG, OF RUTHERFORD, NEW JERSEY, ASSIGNOR TO UNDERWOOD TYPEWRITER COMPANY, OF NEW YORK, N. Y., A CORPORATION OF NEW JERSEY.

TYPE-WRITING MACHINE.

965,347.

Specification of Letters Patent. Patented July 26, 1910.

Application filed July 30, 1909. Serial No. 510,393.

To all whom it may concern:

Be it known that I, RICHARD W. UHLIG, a citizen of the United States, residing in Rutherford, in the county of Bergen and 5 State of New Jersey, have invented certain new and useful Improvements in Type-Writing Machines, of which the following is a specification.

This invention relates to the devices employed in typewriting machines for releasing the platen from the control of the usual notched line-space wheel, so that the platen may be rotated freely while the line-space wheel is held stationary by its spring check.

10 The object of the invention is to produce an inexpensive device of this character, which shall be simple, compact, easily operated, effective and readily applied to existing machines.

15 In the preferred form of the invention, a disk or head is fixed to the end of the platen axle and carries a pair of pivoted dogs, each of which has jaws to bite a flange or ring which projects from the side of the 20 line-space wheel. These dogs are pivoted on said head at points substantially coincident with or near the jaws. Said ring and said jaws are located close to the periphery of the line-space wheel, and the dogs extend 25 therefrom inwardly or toward the platen axle and are operated by their inner ends, a powerful purchase being thus secured to cause the jaws to bite the flange. A releasing button is connected to a stem which is 30 movable longitudinally of the platen axle and has a lug to engage said dogs to operate them.

35 Other features and advantages will hereinafter appear.

40 In the accompanying drawings, Figure 1 is a view of the platen and platen frame of an Underwood front strike writing machine with the present improvements applied thereto. Fig. 2 is a side view partly in section taken on line *a—a*, Fig. 3, showing the improved clutching mechanism in locked or connected position. Fig. 3 is a sectional view taken on line *b—b*, Fig. 2, also showing the clutching mechanism in locked or connected position. Fig. 4 is a similar view 45 showing the clutching mechanism in released position. Fig. 5 is a view of the several parts of the clutching mechanism in

perspective. Fig. 6 is a detail illustrating in perspective one of the locking dogs or levers. 55 Fig. 7 is a view of one end of the platen axle and the disk or head fixed thereto.

The usual cylindrical platen 1 is secured to an axle 2 by screws and is journaled in a platen frame, whose ends are seen at 3. A 60 toothed line-space wheel 4, mounted loosely outside of the platen frame, is usually engaged by a check or detent 5. Upon the outer side of the line-space wheel is formed a ring or flange 6, which is intended to be 65 bitten by the dogs to lock the line-space wheel to the platen. A dog-carrying disk or head 7 is provided upon one side with a hub 9, whereby it is brazed or otherwise fixed upon the end of the platen axle 2. 70

The clutching dogs are designated as 11, and are pivoted at 12 in bosses 13 provided upon the head 7. A C-shaped spring 10 engages slots 14 formed in the lower or inner ends of the dogs (Fig. 6), and tends to draw 75 said dogs together, and thereby release the platen. Near its upper or outer end, each dog is transversely slotted at 15 to form opposing jaws (designated as 20 and 21, at Fig. 3), which bite the ring 6. It will be 80 seen that the pivot pin 12 is in line with the slot 15, or in other words, that the jaws of each dog are close to the axis of rotation, so that a strong purchase is secured for operating the dogs by their lower or inner 85 ends, at Fig. 3.

The dogs are operated by means of a button 16, which is secured upon the end of a stem 17 that extends longitudinally through a long hub 7^a provided on the head 7. The 90 stem 17 has a sliding fit in a hub 25 which is provided upon a finger wheel 26 and inserted in the hub 7^a, and fixed to the latter by a set screw 28 (Fig. 1) or otherwise.

Upon the inner end of the stem 17 is secured a lug 18 which plays in a slot 8^a in the hub 8, and is intended to operate as a wedge to act upon beveled or chamfered faces 19 formed on the inner ends of the dogs, to force them apart or swing them 100 from the position at Fig. 4 to the position at Fig. 3, and thereby cause their jaws to bite the ring 6. The parts are normally held in these positions by a spring check 23 engaging the lug or wedge 18. 105

It will be observed that the flange or ring

6 is close to the periphery of the line-space wheel 4, so that the dogs have a much better purchase on the wheel than in prior constructions (where the flange has been located 5 relatively close to the axis of rotation of the line-space wheel.) This purchase permits the use of a relatively small dog or dog lever, thus permitting the parts to be compactly assembled and easily controlled. It 10 is found that an arm or lever 11, so short as to extend only a part of the distance from the ring 6 toward the platen axle 9, may be sufficiently powerful to give the required bite of the dog upon the ring; it will also 15 be seen that the dogs are loosely pivoted at 12 in a manner to swing in a plane transverse to the platen axis, from the position at Fig. 3 to that at Fig. 4.

To release the platen, it is only necessary 20 to pull the button 16 toward the left or in a direction longitudinal of the platen axle. The lug 18 will pass by the check 23 and withdraw from the dogs, permitting the spring 10 to swing the latter to the released 25 position at Fig. 4. Pressure of the button 16 to the right will relock the platen to the line-space wheel.

Variations may be resorted to within the 30 scope of the invention, and portions of the improvements may be used without others.

Having thus described my invention I claim:

1. In a typewriting machine, the combination with a platen element and a loose line-space wheel element, of an annular flange 35 projecting laterally from one of said elements near its periphery, a dog having a jaw fitting loosely over said flange, said dog pivoted in proximity to said jaw to 40 swing in a plane transverse to the platen axis and comprising a lever extending from said flange toward the axis of rotation of the platen, and a finger piece having means 45 engaging the inner end of said lever to cause it to swing and bite said flange.

2. In a typewriting machine, the combination with a platen element and a loose line-space wheel element, of an annular flange 50 projecting laterally from one of said elements near its periphery, a dog having a jaw fitting loosely over said flange, said dog pivoted in proximity to said jaw to swing in a plane transverse to the platen axis and comprising a lever extending from said flange 55 toward the axis of rotation of the platen, and a finger piece having means engaging the inner end of said lever to cause it to swing and bite said flange; said lever being beveled at its inner end and said finger piece 60 having a stem movable longitudinally of the platen axis and having a lug to engage said bevel and swing the dog.

3. In a typewriting machine, the combination with a platen element and a loose line-

space wheel element, of an annular flange 65 projecting laterally from one of said elements near its periphery, a dog having a jaw fitting loosely over said flange, said dog pivoted in proximity to said jaw and extending from said flange toward the axis of rotation 70 of the platen, and a finger piece having means engaging the inner end of said dog to cause it to swing and bite said flange; said dog being beveled at its inner end and said finger piece having a stem movable longitudinally of the platen axis and having a lug to engage said bevel and swing the dog; means being provided to hold said finger piece in the dog-releasing position.

4. In a typewriting machine, the combination with a platen element and a loose line-space wheel element, of an annular flange 80 projecting laterally from one of said elements, a pair of dogs having jaws fitting loosely over said flange and pivoted in proximity to said jaws to swing in a plane transverse to the platen axis and comprising levers extending from said flange toward the axis of rotation of the platen, and a finger piece having means engaging the inner ends 85 of said levers to cause the dogs to swing simultaneously to bite said flange.

5. In a typewriting machine, the combination with a platen element and a loose line-space wheel element, of an annular flange 90 projecting laterally from one of said elements, a pair of dogs having jaws fitting loosely over said flange and pivoted in proximity to said jaws to swing in a plane transverse to the platen axis and comprising levers extending from said flange toward the axis of rotation of the platen, a finger piece having means engaging the inner ends 95 of said levers to cause them to swing simultaneously to bite said flange, and means to hold the dogs in effective positions.

6. In a typewriting machine, the combination with a platen element and a loose line-space wheel element, of an annular flange 110 projecting laterally from one of said elements, a pair of dogs having jaws fitting loosely over said flange and pivoted in proximity to said jaws to swing in a plane transverse to the platen axis and comprising levers extending from said flange toward the axis of rotation of the platen, a finger piece having means engaging the inner ends 115 of the lever portions of said dogs to cause them to swing simultaneously to bite said flange, and means to hold the dogs in effective positions; said dogs being beveled at their inner ends, and said finger-piece having a stem movable longitudinally of the platen axis and having a lug to engage said bevels and swing 120 the dogs apart.

7. In a typewriting machine, the combination with a platen element and a loose

- line-space wheel element, of an annular flange projecting laterally from one of said elements, a pair of dogs having jaws fitting loosely over said flange and pivoted in 5 proximity to said jaws to swing in a plane transverse to the platen axis and comprising levers extending from said flange toward the axis of rotation of the platen, a finger piece having means engaging the inner ends of the lever portions of said dogs to cause them to swing simultaneously to bite said flange, and means to hold the dogs in effective positions; said dogs being beveled at their inner ends, and said finger-piece having a stem movable longitudinally of the platen axis and having a lug to engage said bevels and swing the dogs apart; and the latter being provided with returning means.
- 10 8. In a typewriting machine, the combination with a platen, a platen axle and a line-space wheel, of a flange projecting laterally from the line-space wheel, a head fixed on said axle, a dog on said head and having jaws to bite said flange and pivoted in proximity to said jaws and extending toward the platen axle to swing in a plane transverse to the platen axis and comprising a lever, a finger piece connected to 25 means to operate said lever.
9. In a typewriting machine, the combination with a platen, a platen axle and a line-space wheel, of a flange projecting laterally from the line-space wheel, a head fixed on said axle, a dog on said head and having jaws to bite said flange and pivoted in proximity to said jaws and extending toward the platen axle to swing in a plane transverse to the platen axis and comprising a lever, a finger piece mounted on 35 a stem which is movable longitudinally axially of said head, and having a lug to engage said lever to operate the same.
10. In a typewriting machine, the combination with a platen, a platen axle and a line-space wheel, of a flange projecting laterally from the line-space wheel, a head fixed on said axle, a dog on said head and having jaws to bite said flange and pivoted in proximity to said jaws and extending toward the platen axle, and a finger piece mounted on a stem which is movable longitudinally axially of said head, and having a lug to engage said dog to operate 45 the same; said head having on one side a part which is fixed to the platen axle, and having on the opposite side a hub in which is fixedly inserted the hub of a platen-rotating finger wheel; said stem passing longitudinally through said finger-wheel hub.
11. In a typewriting machine, the combination with a platen, a platen axle and a line-space wheel, of a flange projecting laterally from the line-space wheel, a head fixed on said axle, a dog on said head and having jaws to bite said flange and pivoted in proximity to said jaws and extending toward the platen axle, and a finger piece mounted on a stem which is movable longitudinally axially of said head, and having a lug to engage said dog to operate the same; said head having on one side a part which is fixed to the platen axle, and having on the opposite side a hub to which is fixed a platen-rotating finger wheel; said stem passing longitudinally through said finger wheel and said hub.
12. In a typewriting machine, the combination with a platen and an axle therefor, of a line-space wheel having a flange or ring and loosely mounted, a head fixed to the platen axle; a pair of dogs or levers mounted on said head to swing in a plane transverse to the platen axis and comprising levers provided with jaws to bite said ring, and means to engage the extremities of the levers to operate them; each of said dogs having opposing jaws to engage and bind said flange or ring.
13. In a typewriting machine, the combination with a platen and an axle therefor, of a line-space wheel having a flange or ring and loosely mounted, a head fixed to the platen axle; a pair of dogs or levers mounted on said head to swing in a plane transverse to the platen axis and comprising levers provided with jaws to bite said ring, a stem, a wedge mounted upon the stem, and a button mounted at the end of the stem and movable longitudinally of the axle to force the wedge between the ends of the levers to force them apart and cause their jaws to bite.
14. In a typewriting machine, the combination with a platen and an axle therefor, of a line-space wheel having a friction flange or ring and loosely mounted on the platen axle, a plate provided with a circumferential flange and a shouldered projection fixed to the platen axle, a pair of dogs or levers mounted in suitable bearings provided in said plate, said dogs or levers being provided with jaws or slots adapted to engage the friction flange or ring of the line-space wheel, side slots and chamfered extremities, a spring positioned upon said plate beneath the shouldered projection with its ends entering the side slots and bearing with spring tension against the dogs or levers to hold them in unlocked position; means for expanding the chamfered extremities of the dogs or levers to cause the slots or jaws thereof to engage the flange or ring of the line-space wheel to connect or bind the latter to the platen, said means comprising a rod slidable along the platen axle, a wedge mounted upon the rod, an operating button mounted upon the other end of the rod, said button and rod movable along the platen

axle to operate said wedge to engage the
chamfered ends of the dogs or levers and in-
sert the same therebetween to force apart
and oscillate the dogs or levers to cause their
jaws or slots to frictionally engage the
flange or ring of the line-space wheel, and a
spring fixed to the sleeve of the plate and

having its free end bearing upon the wedge
to hold the line-space wheel in platen locked
position.

RICHARD W. UHLIG.
